UNITED STATES PATENT OFFICE.

NATHAN M. LOWER, OF PITTSBURGH, PENNSYLVANIA, ASSIGNOR TO LOCOMOTIVE STOKER COMPANY, OF SCHENECTADY, NEW YORK, A CORPORATION OF PENNSYLVANIA.

LOCOMOTIVE-STOKER.

1,379,306.

Specification of Letters Patent.

Patented May 24, 1921.

Original application filed September 2, 1915, Serial No. 48,619. Divided and this application filed February 19, 1917. Serial No. 149,564.

To all whom it may concern:

Be it known that I, NATHAN M. LOWER, a citizen of the United States, and resident of Pittsburgh, county of Allegheny, and State 5 of Pennsylvania, have invented certain new and useful Improvements in Locomotive-Stokers, of which the following is a specification and which are illustrated in the accompanying drawings, forming a part thereof.

10 This application is a division of my application Serial No. 48,619, filed September 2, 1915.

The invention appertains to that type of locomotive stokers in which the fuel is transferred from the coal bin of the tender to the fire-box of the engine by means of screw conveyers, the improvement relating especially to the transferring mechanism.

15 The objects of the invention are to secure simplicity of construction, operation and control, together with reliability of action. Minor objects are secured as hereinafter pointed out.

20 The invention consists in a structure such as is hereinafter described and which is capable of various mechanical changes without departing from the spirit of the invention, and as illustrated in the accompanying drawings, in which—

25 Figure 1 is a detail vertical longitudinal section of the rear end of a locomotive, and the forward end of its tender, taken centrally through the stoking mechanism;

30 Fig. 2 is a detail vertical transverse section through the cab of the locomotive and a portion of the stoking mechanism, showing the rear wall of the fire-box in elevation, some parts being broken away;

35 Fig. 3 is a view partly in section from the plane of the line 3—3 of Fig. 1, some parts being omitted and a portion of the drive and reversing mechanism being shown in section.

40 Fig. 4 is a detail sectional view of a part of the driving mechanism;

45 Fig. 5 is a detail transverse vertical section through the tender back of the conveying mechanism;

50 Fig. 6 is a detail, some parts being broken away, of the ratchet and pawl connection in the driving mechanism;

55 Fig. 7 is a detail longitudinal section through the upper portion of the casing of the elevating screw;

Fig. 8 is a transverse section on the line 8—8 of Fig. 7;

Fig. 9 is a detail of a locking pin;

Fig. 10 is a detail of the regulating valve for controlling the fluid supply to the motor;

Fig. 11 is a detail section on the line 11—11 of Fig. 1; and

Fig. 12 is a detail of a splitting blade used in the stoker.

A part of the frame of the locomotive is represented at 15, the floor of its cab at 16, 65 and the rear wall or back head of its fire-box at 17. A portion of the tender is shown at 18, the floor of its fuel bin being shown at 19. A trough 20 is mounted on the tender below the floor of its fuel bin, this floor having an opening over the trough to which is applied a cover plate 21, which may be slideable to admit fuel to the trough.

At the forward end of the trough and forming a continuation thereof, there is provided an internally ribbed shell 22, from which there leads forwardly to the locomotive a cylinder 23. This cylinder is connected at its forward end to a hollow casting 24 by a universal joint 25 of the ball and socket type, and from the casting 24 there leads upwardly through the floor 16 a cylinder 26 having near its upper end a lateral elbow 27, leading to an opening 28 in the fire-box wall 17. The trough, the shell 22, the cylinder 23, the hollow casting 24, the cylinder 26, the elbow 27, and the opening 28 constitute a continuous conduit through which the fuel, received through the opening in the tender floor, is delivered 90 to the fire-box.

Located upon the axis of the trough 20, the shell 22, and the cylinder 23, is a shaft 29, upon which is mounted a screw conveyor 30 within the trough, a ribbed crusher 95 cone 31 within the shell, and a screw conveyor 32 within the cylinder. Upon the axis of the cylinder 26 there is located a hollow shaft 33, carrying an elevating screw 34. Within the forward end of the trough 100 20 there may be fixed a splitting blade 35, against the edge of which large lumps of fuel will be forced by the action of the screw 30, so as to reduce them to a proper size to enter the shell 22. By the action of 105 this shell and the cone 31, the fuel is crushed to a size suitable for delivery to the fire-box. When the fuel-crushing mechanism is

not employed the cone 31 may be omitted, the screws 30 and 32 being continuous. The screw 30 will force the fuel through the crusher and deliver it to the screw 32, which 5 in turn delivers it directly to the lower end of the screw 34, by means of which it is elevated and delivered to the opening 28. Any suitable means for forcibly discharging the fuel from the opening 28 into the fire-box 10 may be employed. There is indicated for this purpose a nipple 36, to which steam or compressed air may be led by any suitable connection.

The shafts 29 and 33 are driven by any 15 suitable motor. For this purpose there is shown a reciprocating engine 37, of the construction described in a pending application (Serial No. 48,619, filed September 2, 1915), on another form of stoker, and which is, 20 therefore, not here shown in detail.

The motor 37 is shown as suitably mounted on a frame 15 of the locomotive, below the floor 16, its axis being approximately vertical. A rack bar 38 is attached to the end 25 of the motor piston rod 39, and reciprocates within a casing 40, engaging and driving a gear wheel 41, keyed upon a tubular shaft 42 in driving connection with a shaft 43, upon which the shaft 42 is sleeved, through 30 a ratchet and pawl (Figs. 2, 3 and 6). The ratchet wheel 44 is keyed upon the shaft 43, and with it coöperates a pair of pawls 45 and 46, carried by a casing 47 fixed upon the shaft 42. The pawls are connected by 35 means of a retractile spring 48, which urges both toward the ratchet. An oscillatable cam lifter plate 49 is located between the two pawls, and may be shifted to disengage either or both from the ratchet. The plate 40 49 is carried by a circular plate 50, oscillatably mounted in one end, 51, of the casing 47. A lever 52 is fulcrumed at 53 on the end plate 51, near its outer edge, and has a finger 54 entering an aperture in the 45 plate 50. The inner end of the lever 52 has a laterally projecting finger 55, which rides upon a cone 56, slidably mounted on the outer end of the shaft 43.

The cone is controlled by means of a lever 50 57, having attached thereto a pull rod 58, within convenient reach of the operator, which has notches, as 59, for engaging a bracket 60. When the plate 49 and the cone 56 are in the positions shown, the pawl 46 55 is in service and the elevating screws are driven in the feeding direction. By shifting the cone 56 to the left, the lever 52 is swung on its pivot by a spring 52^a to turn the plate 50, thereby raising the pawl 46 60 and permitting the pawl 45 to approach, and, if desired, engage the ratchet 44 in order to first entirely disconnect the motor from the conveying mechanism and then reverse the direction of the shaft 43.

65 The shaft 43 carries a double bevel gear

61 (Fig. 2), one face of which meshes with a bevel gear 62, keyed upon a shaft 63 which extends to and beyond the rear end of the trough 20. The shaft 63 is provided with a universal joint 64, and is telescopic, as indicated at 65, for the purpose of compensating for the relative movements of the locomotive and tender. Upon the rear end of the shaft 63 there is mounted a pinion 66, which meshes with a gear wheel 67, fixed 75 upon the shaft 29.

The opposite face of the bevel gear 61 meshes with a bevel gear 68, mounted upon a short shaft 69, which also carries a spur gear 70, meshing with a similar gear 71, 80 fixed upon the lower end of a shaft 72, which extends through the shaft 33. Upon the upper end of the shaft 72, and above the cylinder 26, there is mounted a casing 73, carrying a pawl 74 which coöperates 85 with a ratchet wheel 75, keyed upon the shaft 33, whereby the latter shaft with its screw 34 is driven in the elevating direction. Upon the reversal of the drive of the shaft 43, as hereinafter described, the pawl 90 74 slides over the teeth of the ratchet 75, leaving the screw 34 at rest. Should it be desired to reverse the direction of rotation of the screw 34, a pin 76 may be inserted through an aperture 77 in the casing 73, and 95 into an aperture 78 in the ratchet wheel 75, thereby locking the casing and the wheel together.

A suitable governor may be used for regulating the speed of the motor, and may be 100 conveniently applied to the upper end of the shaft 72. As shown, this governor comprises a pair of weighted arms 79 and 80, pivotally attached to the shaft, and having shoulders 81 and 82 which bear against an 105 annularly channelled disk 83, slidably mounted upon the shaft 72, and advanced toward the shoulders of the weighted levers by a spring 84, reacting against a nut 85, in threaded engagement with the end of the 110 shaft 72. A lever 86, shown as fulcrumed upon a casing 87 inclosing the governing mechanism and supported by means of a bracket 88, is attached to the stem 89 of a regulating valve 90, for controlling the steam 115 passage leading to the motor cylinder 37. By the action of the spring 84, the valve 90 is normally held open. As the weights 79 and 80 move out in response to centrifugal force, the disk 83 is raised and 120 the valve advanced toward its seat. The governing speed may be regulated by means of the nut 85 for varying the tension of the spring 84.

The splitting blade 35 is removably attached to a bridge fixed across the trough 20 by any suitable means, as the screws 91, 91, whereby it may be easily removed for repairs.

The trough 20 is in loose sliding engage- 130

ment with a chair 92, in order to compensate for the relative movement of the locomotive and tender. Upon the trough 20 there is mounted an apertured plate 93, which is urged upwardly against the floor 19 of the tender by means of springs 94 and 95, thereby preventing the escape of fuel over the edges of the trough, the plate 93 being provided with a depending flange 96 fitting 10 within the trough.

By the construction described, a continuous passage or conduit is provided for the fuel leading from the trough 20 to the fire-box, and unobstructed by any driving or other mechanism. The forward end of the shaft of the transferring screws 30 and 32 may, as shown, float within this conduit. The screw 32 delivers directly to the screw 34. The elevating screw 34 is driven at a 20 higher speed than the transferring or horizontal screw, for the reason that any elevating screw delivers more slowly than a screw having no lifting work to perform.

Should the feed be clogged, as by the 25 presence of extraneous matter, the transferring screws and crusher cone may be reversed by the means described, the elevating screw, however, remaining at rest, and thus holding the fuel which may be within the 30 cylinder 26. Should the clogging occur within the elevating cylinder, the screw 34 may be reversed by introducing the pin 76, it being desirable, however, to first withdraw the fuel within the horizontal portion 35 of the conduit.

No claim is here made for crushing mechanism shown and described. For the purposes of this application this mechanism may be regarded as a part of the horizontal 40 conveyor.

While a desirable and efficient embodiment of the invention is herein shown and described, various changes of detail may be made without departing from its scope.

I claim as my invention—

1. In combination, a locomotive having a firebox, a tender having a fuel bin, a continuous conduit leading forward horizontally below the bin and upwardly and delivering into the fire box through the rear wall thereof, transferring screws in each of the named sections of the conduit the shaft bearings of the screws being outside of the conduit passage, and means for driving the 55 screws and being connected therewith exteriorly of the conduit.

2. In combination, a locomotive having a fire-box, a tender, a conduit for transferring fuel from the tender to the locomotive, a 60 conveyer in said conduit, a conduit leading from the transferring conduit upwardly to the fire-box, a conveyer for elevating fuel therein, operating mechanism for the transfer conveyer connected thereto at its tender 65 end, and operating mechanism for the ele-

vating conveyer connected thereto at its upper end.

3. In combination, a locomotive having a fire-box, a tender, a tubular conduit for transferring fuel from the tender to the locomotive, a screw conveyer in the conduit, a conduit leading upward from the transferring conduit to the fire-box, a screw conveyer therein, operating mechanism connected to such screws at their relatively remote ends. 70

4. In combination, a locomotive having a fire-box, a tender having a fuel bin, a conduit leading from the tender below the fuel bin to the locomotive and upwardly through 80 the floor thereof and entering the fire-box, screw conveying means within both sections of the conduit, and driving means connected with such conveying means at their relatively remote ends. 85

5. In combination, a locomotive having a fire-box, a tender having a fuel bin, a conduit comprising two directly connected sections one leading from the fuel bin and the other delivering to the fire-box, a screw conveyer in each section, means for driving both screws, and means for reversing the screw in the conduit section leading from the tender independently of the other screw. 90

6. In combination, a locomotive having a fire-box, a tender having a fuel bin, a conduit comprising two directly connected sections one leading from the fuel bin and the other delivering to the fire-box, a screw conveyer in each section, means for driving both screws, means for reversing the screw in the conduit section leading from the tender independently of the other screw, and means for reversing the other screw. 95

7. In combination, a locomotive having a fire-box, a tender having a fuel bin, a conduit comprising two directly connected sections one leading from the fuel bin and the other delivering to the fire-box, a screw conveyer in each section, a motor, reversible driving mechanism connecting the motor to the screws and being normally connected with one of said screws only when reversed. 105

8. In combination, a locomotive having a fire-box, a tender having a fuel bin, a conduit comprising two directly connected sections one leading from the fuel bin and the other delivering to the fire-box, a screw conveyer in each section, a motor, reversible driving mechanism connecting the motor to 115 the screws and being normally connected with one of said screws only when reversed, and means for connecting the other of said screws to such mechanism when reversed. 120

9. In locomotive stoking mechanism, in combination, a tender having an apertured floor, a transferring conduit movably mounted below the floor and receiving through the aperture therein, and a spring-supported apertured plate carried by the conduit and 125 130

- having bearing contact with the floor and surrounding the aperture thereof, such plate being provided with a depending flange extending into the conduit.
5. 10. In combination, a locomotive fire-box, a fuel bin, a conveyer for transferring fuel from the bin to the locomotive, a conveyer receiving from said transfer conveyer and elevating the fuel to the fire-box, and means 10 for reversing the direction of rotation of one of said conveyers independently of the other.
11. In combination, a locomotive fire-box, a fuel bin, a conveyer for transferring fuel from the bin to the locomotive, a conveyer 15 receiving from said transfer conveyer and elevating the fuel to the fire-box, power mechanism, and ratchet mechanism for driving both of said conveyers in one direction and for normally driving the transferring conveyer only in the reverse direction. 20
12. In combination, a locomotive having a fire-box, a tender having a fuel bin, a transferring screw below the fuel bin and leading to the locomotive, an elevating screw on the locomotive, means for driving the transferring screw in either direction and for normally driving the elevating screw in one direction only. 25

NATHAN M. LOWER.
